COLLAPSIBLE PIT PROP AND THE LIKE

Walter Sylvester, Scotia Works, Tunstall, England

Application July 30, 1938, Serial No. 222,193
In Great Britain April 29, 1938

8 Claims. (Cl. 248—351)

This invention relates to collapsible pit props of the kind having a movable head with an inclined (flat or curved) lower surface engaging a complementary surface on the end of the prop, and having locking means to secure the head in position on the end of the prop, the inclination of the said surface being such that the movement of the head down the surface shortens the effective length of the prop to enable withdrawal.

Whilst the most general use of these props is in a vertical position with the head uppermost, as roof supports in mines, they are of course capable of use as thrust members in other dispositions, for instance, as horizontal stays in a trench or excavation, but to achieve clarity of description will be referred to only in connection with their use vertically. The invention is applicable to wedge-type props and also to those not of that type, and may be applied to props having posts of H section or of round, square or other section.

The primary essentials in a pit prop are (a) its safety factor, i. e., its ability to support a heavy load, (b) its ability to withstand the rough usage and abuse which obtains in a coal mine or the like, and (c) the readiness with which it may be set up and removed.

The main object of the present invention is to provide constructions of collapsible pit props whose load-carrying power is high but which may when desired be collapsed with the expenditure of very little energy; which cannot be set up to support a heavy load until locked against collapsibility; and which require to be unlocked before any strong pull (which might damage the locked prop) can be exerted on the collapsing mechanism.

According to the invention, the improved prop is characterised in that the locking means comprises one or more catches engaging a part of the head and pivotally mounted so that the head-engaging surface of each catch moves simultaneously with and away from the co-acting part of the head as the head moves on its inclined surface. Preferably the catch is in the form of a lever.

According to a further feature of the invention, the locking means also comprises a two-purpose member adapted in one position to prevent release of the catch or catches, and adapted also, when removed from that position to connect pulling mechanism to the catch or catches.

The invention may be still further characterised in that the part of the pulling means to be attached to the catch or catches is so shaped,

and is so positioned when attached, that the first pull releases the catch or catches from a retaining member, which previously was locked by the said two-purpose member.

The invention is illustrated in the accompanying drawing, wherein:

Fig. 1 is a side elevation of the upper part of a wedge-type collapsible prop in a locked condition;

Fig. 2 is a front elevation of the same;

Fig. 3 is an elevation of the same from the opposite side to Fig. 1, but in the collapsed position;

Fig. 4 is a fragmentary side view showing the operation of the pulling mechanism to release the catch; and

Fig. 5 is a side view of a modification herein-after described.

Referring to Figs. 1 to 4, the prop comprises a strut and a head, the strut or post being made from a suitable length of steel (for example 4" x 4" H section), a foot (not shown) being formed in any required way to suit conditions. The upper end of the strut 1 is cut at an angle and a plate 2 is welded thereto so as to provide a flat inclined surface, the plate 2 extending beyond the strut at the front, and the extending part being supported by the webs or brackets 3 welded thereto and to the strut. The upper corner of the plate at the lower edge is rounded (see Fig. 1) to facilitate the final movement of the head.

In the webs 3 is journaled a pivot pin 4 for a locking lever 5, the pivoted end of the lever being of flat disc form and having a beak or hook 6 adapted to enter and pass through a hole in the extending part of the plate 2. The lower end of the lever 5 is cranked inwardly at 6^a, and has a through hole 7, its extreme lower end lying against the front flange of the strut 1 between L shaped guides 8 welded to such flange.

Slidably in the L shaped guides 8 is a retaining plate 9, the centre portion of which is outwardly bent so as to bridge over the tail end of the lever 5. Such plate 9 has an inwardly directed flange 9^a, which lies below the tail of the lever 5, and is obstructed thereby, and also has a downwardly extending skirt, at a lower level than the flange 9^a. Rivets 10 in the front flange of the prop limit the up and down movements of the retaining plate 9, when the lever 5 is lifted away from the strut.

Placed in a hole in the front flange of the strut is one arm 11 of a right-angled pin, the other arm 12 of which, when vertical, lies against the strut and projects up behind the skirt of the

plate 9, and also supports that plate by the flange 9^a.

The locking lever 5 is of robust structure formed with its central portion adapted to serve 5 as a hand grip or handle.

The head is of box-like form having an inclined lower plate 13 to lie on and slide down the inclined surface 2 on the end of the post, and also having sides 14 to locate it on the post.

10 In the construction shown, the head comprises the two side plates 14, each creased to receive the inclined plate 13, and a surrounding band 15 at the top, the whole being welded together. Placed in the upper end of the head is the loose

15 block or cap 16, the complete removal of which is prevented by the attached stops 17 which are obstructed by the band 15, and a wedge 18 is provided between the plate 13 and the block 16, the wedge being recessed at 18^a on its sides and being held captive in the head by the screws or

20 pins 19 which project into such recesses. The head itself is held captive to the strut by the screws or pins 20, the ends of which lie between the flanges of the strut and between the plate 2 and cross pieces 21. The inclined plate 13 of

25 the head extends beyond the front so as to project over the extended part of the plate 2, and in such portion of the plate 13 is formed a rectangular slot 22, one edge of which is adapted

30 to be engaged by the beak or hook 6 of the catch lever 5. This edge of the slot is preferably rounded so as to avoid any undue friction or abrasion between the hook and the plate during release of the head.

35 The lever 5 is adapted to be attached at the hole 7 to a shackle 23, one end of which is formed with a short beak-like part. The shackle 23 may be placed over the lower end of the lever 5, and the locking pin 11-12 extracted from below the retaining plate 9, and inserted as a pivot to attach the shackle to the lever. This dual use of the pin ensures that the sliding locking piece is free to fall before the shackle can be attached.

In operation, with the parts as shown in Figs. 45 1 and 2, the locking pin is first rotated to the position shown in dotted lines in Fig. 2, whereupon it may be withdrawn and allow the retaining plate to fall. The shackle 23 is now attached to the lever 5 by means of the horizontal part 11

50 of the locking pin and a pull is exerted on the shackle by means of the attached chain. The beak-like part of the shackle, as the shackle is rotated about its pivot by the pulled chain, engages the top part of the retaining plate 9 and displaces it thereby releasing the lever 5 which, by the continued pull of the shackle, is rotated about its pivot 4 to cause the hook 6 to be drawn

55 into the plate 2 and cease to obstruct the sliding of the head down that plate. It will be seen that the load between the plates 13 and 2 does not in any way bind the locking hook 6, since the unlocking movement of that hook is in the direction which the head tends to take under the load.

60 The pivot of the lever 5 is placed as near as is practicable to the head-engaging part of the lever, so that the distance between that pivot and the attached shackle may be several times the distance between that pivot and the head-engaging part, with the result that very little pull on the shackle is sufficient to withdraw the hook 6 into the plate 2.

In resetting the prop, the head is placed in position on the inclined plate 2, the lever 5 is closed down against the flange of the strut, the retaining plate 9 is raised over the tail end of

the lever and the locking pin 11-12 is inserted in position, first horizontally until its part 12 engages the strut flange, whereupon it is turned into a vertical direction so as to lock the retaining plate 9 between itself and the lever 5, whilst 5 being itself locked between the skirt and the strut flange.

In "pulling" the prop, the catch lever kicks up as soon as the retaining plate 9 releases its tail and thus an instantaneous release is obtained. 10

The pulling away of the lever 5 before its tail has been unlocked is prevented since the shackle 23 cannot be attached thereto, unless a pin is used as an attachment, and the necessity for such pin reminds the user that the locking pin 15 11-12 needs to be removed.

Referring now to Fig. 5, the head of the prop may, instead of being a welded built-up unit as shown in Figs. 1 to 4, be a cast unit. In such case, the head will have a forwardly-projecting 20 part with a slot in its lower face, to be engaged by the hook 6, and will have downwardly extending side cheeks to embrace the upper end of the strut, such cheeks carrying inwardly-directed pegs or screws to hold the head captive 25 to the strut. No wedge is employed in this construction.

Instead of the lever 5 and its associate parts being mounted on the outer face of the strut it could be mounted between the strut flanges, and 30 in any case, the method of attaching the sliding retaining plate 9 to the strut may take any suitable form, it being quite common in engineering practice to have one member slidable within or on another.

In order to avoid the trapping of the user's hands between the head and the strut as the head falls, a wedge-shaped spacing member 24 is welded to the side, and limits the downward movement of the head so as to leave room between the head and the strut for the user's fingers. 40

The retaining plate 9 may be provided with a spring, or with a spring-loaded ball, to snap into recesses in the front flange of the strut and prevent the plate's falling by its own weight. This would ensure the locking lever 5 being firmly held until the attached shackle were pulled to dislodge the retaining plate. 45

What I claim is:

1. A collapsible pit prop comprising a strut with inclined upper end face, a head shaped to fit over such inclined face and to slide down it to contract the length of the prop, a locking lever pivotally mounted on the strut and having a projection to engage the head and hold it on the said inclined end of the strut, the projection and pivot co-operating so that the projection can move directionally with the head down the inclined end of the strut during the initial movement for disengagement of the projection and head, and a retaining member slidably mounted on the strut engageable with the end of the locking lever to hold it in the locking position. 50

2. A collapsible pit prop comprising a strut with inclined upper end face, a head shaped to fit over such inclined face and to slide down it to contract the length of the prop, a locking lever pivotally mounted on the strut and having a projection to engage the head and hold it on the said inclined end of the strut, the projection and pivot co-operating to allow sliding movement of the head down the inclined end of the strut during the disengagement of the projection and head, a retaining member slidably mounted on the strut 55

engageable with the end of the locking lever to hold it in the locking position, and a removable member on the strut adapted to hold the slidable retaining member in the lever-holding position.

5 3. A collapsible pit prop comprising a strut with inclined upper end face, a head shaped to fit over such inclined face and to slide down it to contract the length of the prop, a locking lever pivotally mounted on the strut and having a projection to engage the head and hold it on the said inclined end of the strut, the projection and pivot co-operating to allow sliding movement of the head down the inclined end of the strut during the disengagement of the projection and head, a 10 retaining member slidably mounted on the strut engageable with the end of the locking lever to hold it in the locking position, and a removable member on the strut adapted to hold the slidable retaining member in the lever-holding position, the sliding retaining member and removable member co-operating to hold each other in the lever-locking position, the removable member being rotatable to a position where it is free of the sliding member for removal.

25 4. A collapsible pit prop comprising a strut with inclined upper end face, a head shaped to fit over such inclined face and to slide down it to contract the length of the prop, a locking lever pivotally mounted on the strut and having a projection to engage the head and hold it on the said inclined end of the strut, the projection and pivot co-operating to allow sliding movement of the head down the inclined end of the strut during the disengagement of the projection and head, a 30 retaining member slidably mounted on the strut engageable with the end of the locking lever to hold it in the locking position, and a removable member on the strut adapted to hold the slidable retaining member in the lever-holding position, in combination with a pulling means attachable to the locking lever by the removable member whereby attachment of the pulling means entails release of the retaining member.

45 5. A collapsible pit prop comprising a strut with inclined upper end face, a head shaped to fit over such inclined face and to slide down it to contract the length of the prop, a locking lever pivotally mounted on the strut and having a projection to engage the head and hold it on the said inclined end of the strut, the projection and pivot co-operating to allow sliding movement of the head down the inclined end of the strut during the disengagement of the projection and head, a retaining member slidably mounted on the strut engageable with the end of the locking lever to hold it in the locking position, and a removable member on the strut adapted to hold the slidable retaining member in the lever-holding position, in combination with a pulling means attachable to the locking lever by the removable member when

the latter is removed to release the sliding retaining member, whereby attachment of the pulling means entails release of the retaining member, the pulling means comprising a shackle to embrace the locking lever and so shaped that when pulled it first engages and displaces the sliding member to release the locking lever, and then rotates the locking lever to release the head.

5 6. A collapsible pit prop comprising a strut with inclined upper end face, a head shaped to fit over such inclined face and to slide down it to contract the length of the prop, a locking member on the strut to engage the head and obstruct its sliding movement, latching means on the strut to prevent unlocking of the head, and pulling means for 10 first unlatching the locking member, and then unlocking the head by retracting the locking member out of the path of the head in a direction permitting simultaneous sliding movement 15 of the head.

20 7. A collapsible pit prop according to claim 1, wherein the head comprises metal side cheeks welded to a surrounding metal band at their upper end and to an inclined plate intermediate of their ends, such plate extending beyond the front of 25 the head and having a closed aperture therein; wherein the strut comprises a metal post with a flat plate welded to its inclined upper end, such plate extending beyond the front of the strut, and having an open-ended aperture therein; and 30 wherein the locking member comprises a lever pivotally mounted in webs welded below the last-mentioned plate, such lever having a hook-like extension to pass through the apertures in the two plates to lock them together.

25 8. A collapsible pit prop comprising a strut with inclined upper end face, a head shaped to fit over such inclined face and to slide down it to contract the length of the prop, a locking lever pivotally mounted on the strut and having a projection to engage the head and hold it on the said inclined end of the strut, the projection and pivot co-operating to allow sliding movement of the head down the inclined end of the strut during the disengagement of the projection and head, a retaining member slidably mounted on the strut engageable with the end of the locking lever to hold it in the locking position, and a removable member on the strut adapted to hold the slidable retaining member in the lever-holding position, 40 in combination with a pulling means attachable to the locking lever by the removable member whereby attachment of the pulling means entails release of the retaining member, the removable member comprising a lever having a pivot pin attached to it, said pivot pin being of suitable size in diameter and length for use for connecting the pulling member to the locking lever.
